FIG. 4.

INVENTOR
GORDON VARNEY

BY Ernest E. Harmon
ATTORNEY

UNITED STATES PATENT OFFICE

2,015,167

REFRIGERATION

Gordon Varney, Bradenton, Fla.

Application September 5, 1931, Serial No. 561,456

19 Claims. (Cl. 62—104)

This application relates, in general, to the art of refrigeration, and is more particularly related to that phase of this art which is concerned with quick cooling and/or quick freezing; the same being an improvement upon my co-pending applications, Serial Number 542,503, filed June 6, 1931 and Serial Number 544,802, filed June 13, 1931.

Having due regard for the problems involved in quick freezing, as outlined in the applications above mentioned, it is the particular object of this invention to provide a method for quick freezing which shall answer the objectives of both of these prior applications and, in addition, provide some advantages to be found in neither.

It is the prime object of my invention to devise a method of and means for providing for quick freezing which will insure a maximum heat transfer and a minimum of frictional resistance.

To this end, it is an object of my invention to provide a refrigerating tube through which the packages to be refrigerated are passed, the refrigerating tube being substantially filled with fluids of differing specific gravities. In my prior applications I have discussed the use of mercury as a fluid for filling the refrigeration tube. For some packages mercury is excellent, having extraordinarily high heat transfer properties and acting as an excellent flotation means for the packages, preventing friction with the base of the tube and insuring contact with the upper walls of the tube for refrigeration. For other more fragile packages the use of a tube entirely filled with mercury would result in so great a pressure against the top walls as to be injurious to the package.

For this reason I have devised an apparatus for and a means of quick freezing in which the refrigerating tube is filled to a certain limited extent with a fluid of relatively high density and high heat conductive properties while the remainder of the tube is filled with a fluid of lower density and yet of relatively high heat conductive properties. The two fluids chosen should be substantially non-miscible, at least one of which is capable of maintaining its own level. For instance, mercury and brine, mercury and "Prestone", mercury and alcohol, mercury or "Prestone" and a fluid gas of high heat conductivity may be used. The use of two such fluids will permit a range of possibilities of operation, each of which is believed to be entirely novel, in which either of the fluids, or both, either may be circulated or substantially static.

In addition to the field of endeavor, as outlined in my preceding applications, this double fluid

idea lends itself particularly well to another application untouched, in my preceding applications, to wit; the manufacture of ice, or the like, commercially. In this case, mercury or some similar fluid of high specific gravity and high heat conductive properties will be used to the amount that it approximately provides flotation for the filled ice containers, while the remainder of the refrigerating tube or device is filled with a fluid of lower specific gravity though of high heat conductivity; the two liquids combining their efforts toward flotation. Such a system not only provides for an extraordinarily high rate of heat transfer but also, by reason of the flotation effect, permits the successive passing of a plurality of articles to be refrigerated through a refrigerating device with a minimum of frictional resistance.

Furthermore, there are instances where certain packages are of relatively high specific gravity and require, for their flotation, a fluid which may have injurious effects upon the package. It is another object of my invention, in such cases, to provide one fluid for the primary purpose of flotation and heat exchange regardless of its action on the contents of the package, and a second fluid, of lower specific gravity, which is of high heat conductivity and which has no deleterious effects on the package.

It is another object of my invention to provide a process of quick hardening of frozen ice cream and like commodities.

Other objects of my invention will be found in the accompanying specification and claims, and will be disclosed in the accompanying drawing, in which:

Figure 1 is a central longitudinal vertical section, substantially diagrammatic, showing my refrigerating tube with a plurality of heat conductive fluids, non-miscible and of differing specific gravities, both of which are substantially static within the tube.

Figure 2 is an enlarged detail of Figure 1.

Figure 3 is a similar view of my refrigerating device in which a substantially static fluid is used for flotation means and a gaseous fluid of high heat conductivity and of qualities inactive with respect to the package to be cooled, is used to fill the remainder of the tube, this gaseous fluid being disclosed as having a separate supplementary means for its further refrigeration.

Figure 4 is a transverse section through a modification of my device particularly adaptable to the commercial manufacture of ice or for the hardening of commodities already frozen.

Referring now with greater particularity to the drawing, my device will be seen to be comprised, as follows:

In Figure 1 I have disclosed a refrigeration chamber 1, having a refrigeration tube 2 extending therethrough. The tube 2 is designed in such a manner as to provide a fluid seal and is disclosed as of a substantially flat U-shaped configuration, the ends 3 and 4 being upturned for this purpose. Any suitable means, such as is disclosed in my preceding co-pending applications, above referred to, may be used for providing for the successive passing of a plurality of articles 5 to be frozen through my refrigerating tube 2. Such a means is schematically disclosed at 6.

Within the tube 2 it will be seen that I have provided, as flotation means, and as heat conductive means, two liquids 7 and 8, the surface level of each being indicated by its reference character. The liquid 7 is of greater specific gravity and may be mercury or some other liquid with similar characteristics of specific gravity and heat conductivity, while the liquid 8 is of lower specific gravity but of high heat conductivity. It will be understood that my invention contemplates the use of a refrigeration tube 2 of a size and cross-sectional configuration approximating that of the package to be frozen.

In Figure 3 I have disclosed a modification of my device wherein a liquid and a gas are used as the two means for providing for heat exchange; the liquid supplying, in addition to its heat transfer properties, the agency of flotation, and the gas, filling that portion of the space in the tube 2 above the liquid, being provided with a separate refrigeration system. The liquid level is shown by character 9, indicative of the liquid and its level, and the gas is indicated by reference character 10. The gas 10 is provided with a separate cooling system indicated by compressor 11 and pipes 12, 13 and 14 in conjunction with a separate refrigerating chamber 15. The gas 10 is selected as one which will be chemically inactive with respect to the article to be frozen.

In Figure 3 I have disclosed a modification of my device particularly adaptable for the quick manufacture of ice commercially or for the quick hardening of ice cream or other frozen commodities. In this structure a substantially U-shaped trough 16 is provided. The trough 16 is provided with a plurality of ducts 17, adjacent the inner surface of the trough, for the admission and circulation of a cooling agent. The trough is partially filled with two or more liquids 18 and 19, which are substantially non-miscible. The fluid 18 is of greater specific gravity and of high heat conductivity, while the fluid 19 is of lesser specific gravity but also of high heat conductivity. Containers 20 are provided for the product to be hardened or frozen, while a cover 21 is provided for the trough. The cover 21 is preferably of a material of low rate of conductivity.

Having described my invention in detail it will be seen that its operation is as follows.

A sufficient quantity of fluid of high specific gravity and high heat conductivity is provided to insure flotation of the packages to be refrigerated. This prevents friction of the packages in their passage through the refrigeration device and also provides for an excellent heat exchange adjacent its base. The liquid or gas 8, 10 and/or 19 of lower specific gravity is selected for qualities of high heat conductivity and non-deleterious action on the package to be frozen. It co-acts with the fluid 75 of higher specific gravity for flotation and heat

exchange. The apparatus shown at 6 is merely a schematic device for providing for successive feeding of a plurality of packages to be frozen and forms, per se, no specific part of this invention.

Having thus described my invention, I claim: 5

1. In a refrigerating apparatus including a refrigerating chamber an article receivable in and adapted to be passed through said refrigerating chamber, the space between the inner walls of said chamber and said article being filled, in 10 part, with a plurality of liquids of high heat conductivity and of differing specific gravities.

2. In a refrigerating apparatus including a refrigerating chamber an article receivable in and adapted to be passed through said refrigerating 15 chamber, the space between the inner walls of said chamber and said article being filled, in part, with a plurality of substantially non-miscible liquids of high heat conductivity and of differing specific gravities. 20

3. In a refrigerating apparatus including a refrigerating chamber an article receivable in and adapted to be passed through said refrigerating chamber, the space between the inner walls of said chamber and said article being filled, in part, 25 with a plurality of liquids of high heat conductivity and of differing specific gravities, one of said fluids being substantially static.

4. In a refrigerating apparatus including a refrigerating chamber an article receivable in and 30 adapted to be passed through said refrigerating chamber, the space between the inner walls of said chamber and said article being filled, in part, with a plurality of substantially non-miscible liquids of high heat conductivity and of differing specific 35 gravities, one of said fluids being substantially static.

5. In a refrigerating apparatus including a refrigerating chamber an article receivable in and adapted to be passed through said refrigerating 40 chamber, the inner walls of the chamber being in intimate thermal contact with the article, and the spaces between said articles and said walls being filled with a plurality of liquids of differing specific gravities. 45

6. In a refrigerating apparatus including a refrigerating chamber an article receivable in and adapted to be passed through said refrigerating chamber, the inner walls of the chamber being in intimate thermal contact with the article, and the spaces between said articles and said walls being filled with a plurality of liquids of high heat conductive properties.

7. In a refrigerating apparatus including a refrigerating chamber an article receivable in and 55 adapted to be passed through said refrigerating chamber, the inner walls of the chamber being in intimate thermal contact with the article, and the spaces between said articles and said walls being filled with a plurality of non-miscible fluids of 60 high heat conductive properties.

8. In a refrigerating apparatus including a refrigerating chamber an article receivable in and adapted to be passed through said refrigerating chamber, the space between the inner walls of 65 said chamber being filled with two liquids of high heat conductivity, one of said liquids being of relatively high specific gravity and the other of relatively low specific gravity.

9. In a refrigerating apparatus including a refrigerating chamber an article receivable in and adapted to be passed through said refrigerating chamber, the space between the inner walls of said chamber being filled with two non-miscible liquids of high heat conductivity, one of said 75

liquids being of relatively high specific gravity and the other of relatively low specific gravity.

5 10. In a refrigerating apparatus including a refrigerating chamber an article receivable in and adapted to be passed through said refrigerating chamber, the article being in intimate thermal contact with the inner walls of the chamber and the space between the inner walls of said chamber being filled with two liquids of high 10 heat conductivity, one of said liquids being of relatively high specific gravity and the other of relatively low specific gravity.

11. In a refrigerating apparatus including a refrigeration chamber an article receivable in and 15 adapted to be passed through said refrigerating chamber, the article being in intimate thermal contact with the inner walls of the chamber and the space between the inner walls of said chamber being filled with two non-miscible liquids of high heat conductivity, one of said liquids being of relatively high specific gravity and the other of relatively low specific gravity.

12. In a refrigerating apparatus including a refrigerating chamber a plurality of articles receivable in and adapted to be passed successively through a refrigerating chamber, the space between the inner walls of said chamber and said articles being filled with a plurality of liquids of differing specific gravities.

13. In a refrigerating apparatus including a refrigerating chamber a plurality of articles receivable in and adapted to be passed successively through a refrigerating chamber, the space between the inner walls of said chamber and said articles being filled with a plurality of non-miscible liquids of differing specific gravities.

14. In a refrigerating apparatus including a refrigerating chamber a plurality of articles receivable in and adapted to be passed successively through a refrigerating chamber, said articles being in intimate thermal contact with the walls of said chamber and the space between the inner

walls of said chamber and said articles being filled with a plurality of liquids of differing specific gravities.

15. In a refrigerating apparatus including a refrigerating chamber a plurality of articles receivable in and adapted to be passed successively through a refrigerating chamber, said articles being in intimate thermal contact with the walls of said chamber and the space between the inner walls of said chamber and said articles being filled with a plurality of liquids of differing specific gravities, one of said liquids being substantially static.

16. As a refrigerating apparatus, a refrigerating chamber, a heat conduction tube extending 15 through said chamber, said tube having a cross-sectional area approximating that of the article to be refrigerated to provide for intimate thermal contact between its walls and the said article, and a plurality of heat conducting liquids filling 20 the space between said articles and said walls.

17. As a refrigerating apparatus, a refrigerating chamber, a heat conduction tube extending through said chamber, said tube having a cross-sectional area approximating that of the 25 article to be refrigerated to provide for intimate thermal contact between its walls and the said article, and a plurality of non-miscible heat conducting fluids filling the space between said articles and said walls.

18. In a refrigerating apparatus including a refrigeration chamber, the method of refrigerating articles which consists in floating the articles through the refrigeration chamber on a plurality of fluids of varying densities.

19. In a refrigeration apparatus including a refrigerating container and a refrigerating tube, a container of water, a refrigerating tube, said tube having a plurality of liquids of differing specific gravities therewithin to provide a means 40 of flotation for said container through said tube.

GORDON VARNEY.
